LAMP SHADE PACKING AND SHIPPING DEVICE

Martin M. Pink, Oak Park, Ill., assignor to Chippewa Paper Products Co., Inc., Chicago, Ill., a corporation of Illinois

Application February 28, 1955, Serial No. 490,886

2 Claims. (Cl. 206—65)

The present invention relates to lampshade packing and shipping devices, and more particularly, to devices to prevent damage to nested lampshades.

In the packing and shipping of lamp shades, considerable difficulty has been experienced in devising a means to keep the shades properly spaced to avoid damage caused by one shade rubbing against the others. Usually the shades are nested when packed for shipment and tend to wedge together. The present invention solves both these difficulties in a very simple, efficient and inexpensive manner and makes possible the shipping of a large number of shades in a single carton.

Essentially, the invention comprises a number of preferably cylindrical slotted sections of at least two different diameters, one adapted to telescope within the other, the sections being themselves maintained in a fixed spaced relation by portions of the lamp shade structure, thereby maintaining the shades in a nested, spaced relation to each other.

Other and further objects and advantages of this invention will become more apparent from a consideration of the following specification when read in conjunction with the annexed drawings, in which:

Figure 1 is a sectional view through a shipping carton, showing a number of lamp shades packed in said carton, the shades being shown partly in elevation and partly broken away.

Figure 2 is an exploded view of a series of spacers constituting the present invention, the spacers being shown in perspective.

Figure 3 is a sectional view taken along the line 3—3 of Figure 1, looking in the direction of the arrows, with parts broken away.

Figure 4 is a fragmentary perspective view of a modified form of the invention.

Now, referring to the drawing, in which like reference numerals indicate like parts throughout the several figures, the reference numeral 10 indicates generally a lamp shade shipping carton in which lamp shades are shipped.

An elongated tubular base member 11 is positioned within the carton 10 and is adapted to receive telescopically a shorter cylindrical member 12. The member 12 is slotted as at 13, with the slot extending a substantial distance through the member 12 in a horizontal direction. A lamp shade 14 having a rib frame 15 at the upper end thereof is positioned with the frame 15 extending through the slot 13 of the member 12, as disclosed in Figure 3 of the drawing. A second cylindrical spacer member 16, having an internal diameter substantially equal to the external diameter of the spacer member 12 is telescoped thereover, with the bottom edge 18 of the member 16

5

engaging the frame 15 of the lamp shade 14. The spacer member 16 is slotted as at 17, in the same manner as the spacer member 12, and is adapted to support another lamp shade 14 having the frame 15 thereof extending through the slot 17.

In the use and operation of this device, alternate spacer members 12 and 16 are telescopically positioned in extended position relative to one another with the frames 15 of the respective lamp shades 14 positioned within the respective slots 13 and 17 thereof, so as to form a nested stack of spaced lamp shades 14 resting on the base member 11 and all contained within the carton 10.

The lampshades 14 are both vertically and horizontally spaced by the spacer members 12 and 16 so that neither the frames 15 nor any other parts of adjacent shades 14 contact each other. This, of course, prevents the shades 14 from having a damaging rubbing contact or from being jammed together in an unspaced nested stack during packing and shipping thereof.

20 In Figure 4 of the drawings, a modified form of the invention is disclosed wherein equispaced parallel slots 19 extend inwardly of a tubular member 20 and the lampshade frame 15 is adapted to be received therein in nesting arrangement in the same manner as is disclosed in Figure 1. It should be understood that a multiplicity of the tubular members 20 will be provided in sizes to permit telescoping as in Figure 1.

Having thus described the preferred embodiments of the invention, it should be understood that minor modifications and changes may be resorted to without departing from the scope of the appended claims.

What is claimed is:

1. In combination a lamp shade having a frame including ribs positioned therein, a support for said shade comprising a container having a tubular member positioned vertically in said container, a short tubular member of lesser diameter than the first tubular member seated in the end of the first tubular member, said short tubular member having a slot extending circumferentially partially around it, the ribs on the frame being positioned in the slot, a second short tubular member having a diameter greater than that of the last named tubular member and having a slot therein, said second tubular member positioned over the first named short tubular member and having its lower end seated on the said ribs and further telescoping short and slotted tubular members stacked one above the other and seated on ribs positioned in the slots of the tubular members.

2. The invention as claimed in claim 1, wherein some 35 of the short tubular members have vertically extending slots at their ends in which the said ribs are positioned.
